WINDOW CONSTRUCTION

Arthur C. Marquardt, Orchard Park, N. Y.

Application January 26, 1937, Serial No. 122,418

6 Claims. (Cl. 20—51)

This invention relates to improvements in windows of the kind in which provision is made for presenting the outer sides of the panes to the interior of the building so that they may be cleaned with facility and without danger. Although not necessarily limited to windows of this type, the invention is characterized by features which adapt it particularly to windows wherein the panes are carried by sashes which are moved in vertical planes as they are opened or closed.

One object of the invention is to provide a construction which will enable sashes of conventional design to be employed and which will permit said sashes to be opened and closed in conventional manner.

A further object is to provide a window of the kind generally described in which the sashes may be moved as a unit when it is desired to present the outer sides of the panes to the interior of the building.

A still further object is to provide a window which is so designed that screens, storm sashes and other appurtenances which are more or less seasonal in use may be attached and detached with facility from the interior of the building.

A still further object is to provide a construction which is weather-tight.

A still further object is to provide a novel design and arrangement of the parts of the window whereby simplicity and economy in construction are obtained.

The invention is illustrated in the accompanying drawings in which:

Figure 1 is a view in elevation of a window embodying the features of the invention.

Figure 2 is a horizontal section taken along line 2—2 of Figure 1.

Figure 2a is a fragmentary sectional view taken along line 2a—2a of Figure 1.

Figure 3 is an enlarged vertical section taken along line 3—3 of Figure 1.

Figure 4 is an enlarged vertical section taken along line 4—4 of Figure 2.

Figure 5 is a detail section taken along line 5—5 of Figure 3.

Figure 6 is a horizontal section taken along line 6—6 of Figure 4.

Figure 7 is an enlarged fragmentary section taken along line 7—7 of Figure 3.

The window, as illustrated, includes upper and lower sashes 10 and 11, respectively, which are of standard construction and which are mounted for movement in vertical planes in a frame 12 so that they may be opened and closed in conventional manner, the said sashes fitting in chan-

nels 13 and 14, respectively, which are formed in the vertical members 15 and 16 of the said frame. Vertical members 17 provide the adjacent inner walls of the channels 13 and 14, the side walls of the said members being resilient and being bent inwardly at their outer ends to provide cam surfaces which co-operate with wedge-like strips 19. The members 17 (Figure 7) are secured to the frame 12 by screws 20 which enter threaded openings formed in the strips 19, the said screws 10 being operative as they are tightened to move the said strips inwardly and hence to spread apart the side walls of the members 17. The screws 20, therefore, may be adjusted to cause the said side walls to engage the sashes 10 and 11 in such a manner that although, when unlocked, they may be opened and closed, at will, they will remain in any position to which they may be adjusted without the aid of weights. The marginal edges of the frame 12 which are located exteriorly of the building delimit an opening in which a screen 20a (Figure 3), or any other similarly shaped appurtenance, may be arranged, the said screen, or appurtenance, fitting against shoulders 20b and being removably secured in the said opening by 25 suitable fastening means 20c.

The frame 12 is mounted in a rectangular casing 21 which is adapted to be incorporated in the wall structure of a building in conventional manner, the bottom cross member 22 of the said casing being formed to provide a sill 22a upon which the bottom cross member 23 of the frame 12 rests. The sill slopes downwardly away from the interior of the building and is formed to provide a ledge 24 against which the cross member 23 fits. The vertical members 15 and 16 of the frame 12 are formed to provide flanges 25 (Figure 2) which extend substantially the full length of the said members, the outer ends of the said flanges preferably being formed to provide rounded edges 27. The vertical members of the casing 21 are indicated at 28 and 29 (Figure 2) and are channel-shaped in cross-section. They provide guides for sealing members 30 and 31, respectively, which are likewise channel-shaped in cross-section, the side walls 32 of the said sealing members being formed to provide shoulders 33 which fit conformably against the rounded edges of the flanges 25 and rearwardly extending flanges 34 which slidably engage the opposite walls of the said casing members. Springs 35 which are carried by the casing members 28 and 29 are connected to the sealing members 30 and 31 and normally bias the latter so that the shoulders 33 thereof are held tightly against the rounded edges 55

of the flanges 25 of the vertical members of the frame 12, thereby providing substantially weather-tight joints.

The upper cross member of the frame 12 is indicated at 36. Normally it fits in a shallow channel 37 (Figure 3) which is formed in the head 38 of a horizontal sealing member 39, the said member having side walls 40 which extend through an opening formed in the upper horizontal cross member 41 of the casing and which slidably engage the walls which delimit the said opening. Normally the sealing member 39 occupies a position in which the head 38 thereof fits tightly against the upper cross member of the frame 12 to provide a substantially weather-tight joint.

The frame 12 is secured in the casing 21 by a sleeve 42 and a spindle 43 (Figures 1 and 3). The former is tubular in cross section; it is suitably secured to the upper cross member 36 of the frame, preferably midway between the side members 15 and 16; it extends through an opening 44 which is formed in the head 38 of the sealing member 39; and it fits over the lower end of a trunnion 45 which is suitably secured by a plate 46 to the upper cross member of the casing. The spindle 43 is suitably secured to the bottom cross member 23 of the frame 12, preferably substantially midway between the side members 15 and 16; and it is journaled in a bushing 47 which is carried by the sill 22a.

Means is provided for reversing the frame 12 in the casing 21. The said means includes a roller 48 which is mounted upon a pin 49. The latter is carried by a sleeve 50 which fits over the spindle 43 and which is secured thereto by an element 51 which extends into an annular groove 50a formed in the said spindle, the said element permitting relative angular movement between the spindle and sleeve while preventing relative axial movement. The roller 48 rides upon a cam 52 which is carried by a shaft 53. The latter is mounted in a bracket 54 which is suitably secured in the lower cross member of the casing. It includes an extension 55 which projects through an opening 56 in the inner side wall of the said member and which carries a crank 57. When the parts occupy the positions shown in Figure 3, the roller 48 engages the lowermost portion of the cam 52. Upon rotation (in a clockwise direction), however, the cam 52 is operative to move the spindle 43, and hence the frame 12, upwardly, the said cam being so designed that as its peak portion moves under the roller 48 the lowermost portion of the lower cross member of the frame 12 is moved to a position slightly above that occupied by the top face of the ledge 24 of the sill. During such upward movement of the frame 12 a part of the spindle 43 moves out of the bushing 47 while the sleeve 42 slides further over the trunnion 45. A second roller 58 engages the inner face of the cam 52, the said roller being carried by an extension of the sleeve 50. The roller 58 co-operates with the cam 52, as the crank 57 is operated to lower the frame 12, to insure return of the latter to its normal position in the event that the weight of the parts is inadequate for this purpose.

The upward movement of the spindle 43 is transmitted to the horizontal sealing member 39 in such a manner that the latter moves a greater distance than the frame 12, whereby when the said frame has been moved to the upper limit of its range of movement there will be a clearance 75 between it and the said sealing member. To this

end levers 60 and 61 are connected at their inner ends to the pin 49 at opposite sides of the sleeve 50. The lever 60 is pivotally mounted intermediate its ends upon a bracket 63 which is suitably secured to the sill-providing wall of the lower cross member of the casing. At its outer end the lever 60 is connected to the lower end of a link 64 which is arranged in the vertical member 28 of the casing and which is connected at its upper end to the outer end of a lever 65. The latter is arranged in the upper cross member of the casing and is pivotally mounted intermediate its ends upon a bracket 67 which is suitably secured to the top wall of the said casing member. The inner end of the lever 65 is connected to a rod 68 which is mounted between the front and rear walls of the sealing member 39 as best shown in Figure 3. At its opposite end the front and rear walls of the said sealing member carry a second rod 69 (Figure 1). The inner end of a lever 70 is connected to the rod 69. The said lever is pivotally mounted intermediate its ends upon a bracket 72 which is suitably secured to the top wall of the upper cross member of the casing. The outer end of the lever 70 is connected to the upper end of a link 73 which is arranged in the vertical member 29 of the casing. The lower end of the link 73 is connected to the outer end of the lever 61. The latter is pivotally mounted intermediate its ends upon a bracket 75 which is suitably secured to the sill-providing wall of the lower cross member of the casing.

It will be noted that as the spindle 43 is moved upwardly to raise the frame 12 the levers 60 and 61 are actuated to move the links 64 and 73 downwardly, this movement of the said links being transmitted to the levers 65 and 70 to raise the sealing member 39. The levers 60 and 61 and 65 and 70 are adapted to move the sealing member through a greater range than is traversed by the frame 12. The sealing member 39, therefore, moves at a faster rate than the said frame. During its upward movement in the manner described the upper cross member 36 of the frame 12 moves out of the channel in the head 45 of the sealing member 39 and at the completion of such movement is located a short distance below said head.

The downward movement of the links 64 and 73 is utilized to move the sealing members 30 and 31 against the action of the springs 35 to provide clearances between the said sealing members and the vertical members 15 and 16 of the frame. For this purpose the said links carry elements 76. The latter are adjustably secured to the said links by bolts 78 and have inclined faces 79 which engage downwardly and inwardly inclined projections 80 formed upon the end walls of the sealing members.

From the foregoing it will be apparent that by moving the crank 57 (in a clockwise direction) through an angle of approximately 180° the frame 12 will be moved to the upper limit of its range of movement, in which position the lowermost edge of the lower member of the frame is located above the ledge 24 of the sill. Simultaneously with such movement of the frame the sealing members 30 and 31 move away from the flanges 25 of the vertical members 15 and 16 of the frame to provide clearances between the said sealing members and the said frame members. At the same time also the horizontal sealing member 39 is moved upwardly to provide a clearance between it and the upper cross member of the frame. In other words upon completion of 75

the movement of the crank 57 clearances are provided between the vertical and horizontal members of the frame 12 and those parts of the casing 21 which normally cooperate with said members to provide substantially weather-tight joints. When the frame 12 has been moved to the position described, it is supported upon the spindle 43. As thus supported it may be rotated through an angle of 180° to present its outer side to the 10 interior of the building. When the frame 12 occupies this position the screen 26a may be removed and applied with facility from the interior of the building as may a storm sash or other similarly shaped appurtenance. Likewise the outer 15 sides of the panes of both sashes may be cleaned with facility. The necessity for performing these operations from the exterior of the building is, therefore, avoided. Upon completion of the desired operations the frame 12 is rotated to its 20 original angular position. The crank 57 is then moved in a counter-clockwise direction. During the return movement of the crank the frame 12 is lowered upon the sill of the casing behind the ledge 24 as shown in Figure 3. Simultaneously 25 with the downward movement of the frame the sealing members 30 and 31 move toward one another and engage the flanges 25 of the vertical frame members as the frame comes to rest upon the sill. At the same time also the horizontal 30 sealing member 39 moves downwardly with, but at a greater speed than, the frame 12 so that as the latter approaches the lower limit of its range of movement the upper cross member of the frame is caused to enter the channel 31 of the said 35 sealing member. The construction described, therefore, is weather-tight and it has the further advantage that it does not interfere in any way with the normal operation of the sashes.

I claim as my invention:

- 40 1. A window construction including a casing, said casing having a sill which is formed to provide a shoulder, a frame in said casing which is adapted to rest upon said sill against said shoulder, said frame being formed to provide 45 guideways, means for providing sealed joints between the sides and top of said frame and the adjacent parts of said casing, sashes movable in said guideways to open and closed positions and means for mounting said frame so that it may be 50 raised to clear said shoulder and then moved to reverse its position in said casing, said first named means being movable to provide clearances between the sides and top of said frame and the adjacent parts of said casing.
- 55 2. A window construction including a casing, said casing having a sill which is formed to provide a shoulder, a frame in said casing which is adapted to rest upon said sill against said shoulder, said frame being formed to provide guideways, sealing members which are carried by said casing and which normally fit against the sides and top of said frame to provide weather-tight joints, sashes movable in said guideways to open 60 and closed position, means for mounting said frame so that it may be raised to clear said shoulder and then rotated to reverse its position in

said casing and means for moving said sealing members to provide clearances between the sides and top of said frame and said casing.

3. A window construction including a casing, 5 said casing having a sill which is formed to provide a shoulder, a frame in said casing which is adapted to rest upon said sill against said shoulder, said frame being formed to provide guideways, sashes movable in said guideways to open and closed positions, sealing members which are carried by said casing and which normally fit against the sides and top of said frame to provide weather-tight joints, a spindle upon which said frame is mounted for rotary movement, means for moving said spindle to raise said frame so that it clears said shoulder and means actuated by said last named means for moving said sealing members to provide clearances between the sides and top of said frame and said casing, whereby said frame may be rotated on said spindle 10 to reverse its position in said casing.

4. A window construction including a casing, 15 said casing having a sill which is formed to provide a shoulder, a frame in said casing which is adapted to rest upon said sill against said shoulder, a sash in said frame which is movable to open and closed positions, means for providing sealed joints between the sides and top of said frame and the adjacent parts of said casing and means for mounting said frame so that it may 20 be raised to clear said shoulder and then moved to reverse its position in said casing, said first named means being movable to provide clearances between the sides and top of said frame and the adjacent parts of said casing.

5. A window construction including a casing, 25 said casing having a sill which is formed to provide a shoulder, a frame in said casing which is adapted to rest upon said sill against said shoulder, a sash in said frame which is movable to open and closed positions, sealing members which are carried by said casing and which normally fit against the sides and top of said frame to provide weather-tight joints, means for mounting said frame so that it may be raised to clear 30 said shoulder and then rotated to reverse its position in said casing and means for moving said sealing members to provide clearances between the sides and top of said frame and said casing.

6. A window construction including a casing, 35 said casing having a sill which is formed to provide a shoulder, a frame in said casing which is adapted to rest upon said sill against said shoulder, a sash in said frame which is movable to open and closed positions, sealing members which are carried by said casing and which normally fit against the sides and top of said frame to provide weather-tight joints, a spindle upon which said frame is mounted for rotary movement, means for moving said spindle to raise said frame 40 so that it clears said shoulder and means actuated by said last named means for moving said sealing members to provide clearances between the sides and top of said frame and said casing, whereby said frame may be rotated on said 45 spindle to reverse its position in said casing.

ARTHUR C. MARQUARDT.
